UNITED STATES PATENT OFFICE.

ALDO TAMMEO, OF GENOA, ITALY, ASSIGNOR OF FOUR-TENTHS TO ALDO TAMMEO,
 FOUR-TENTHS TO EUGENIO CAMINADA, ONE-TENTH TO PIETRO FOPPIANO, AND
 ONE-TENTH TO CARLO SCOTTI, ALL OF GENOA, ITALY.

AEROPLANE.

Application filed April 20, 1925, Serial No. 24,555, and in Italy June 30, 1924.

This invention is based upon the consideration that an aeroplane is a free system in space, pivoted at its centre of gravity, in respect of which the forces and torques in action are balanced, and about which the aeroplane turns.

This invention has for its object to obtain automatic transverse stability of the aeroplane by the provision of combined 10 automatic means for obtaining both longitudinal stability and steering stability independently of the translational speed of the aeroplane.

It is known to those skilled in the art 15 that in certain positions of an aeroplane and steering having regard to the direction of wind, air currents which should produce a thrust in the wing plane to provide the carrying power thereof, in place of being 20 incident with the wing plane, are parallel thereto; as the said carrying power will therefore totally fail, the aeroplane, in default of the characteristic features according to this invention, would begin to side- 25 slip obliquely over the lower wing.

The principle above referred to can easily be demonstrated for, should the aeroplane have a translational speed of sufficient value, the aeroplane is firstly subjected to the direct 30 and quick action of the horizontal longitudinal tail arrangements which provide for longitudinal stability and will rise, so restoring the angles of incidence of the wings to their right value. On the contrary, due 35 to engine failure, should the aeroplane not possess the necessary speed, it will begin to sideslip obliquely over the lower wing, thus causing the means provided for securing the automatic steering stability to take effect.

The fundamental principles above referred to, therefore, come into action and simultaneously provide both for automatic longitudinal stability and a considerable automatic steering stability independently 40 of the translational speed of the aeroplane.

According to this invention the means provided for causing relative automatic stability of the aeroplane about the rolling axis

and complete automatic stability about the pitching axis described in a former application is combined with the means for providing automatic stability about the rolling axis and complete automatic stability about the steering axis described in another application.

The invention is illustrated in the accompanying drawing, in which Figure 1 is a front elevation, Figure 2 a side elevation, and Figure 3 a plan of an aeroplane constructed in accordance with this invention.

As illustrated 1 and 2 are the horizontal balancing planes designed to provide stability of the aeroplane about the rolling axis and about the pitching axis, and to produce a righting action of the aeroplane around the pitching axis should the aeroplane come out of equilibrium, while 3 and 4 are vertical stabilizing planes designed to provide automatic stability with respect to the rolling axis and with respect to the steering axis, and further to produce a righting action with respect to the rolling axis and a corrective action with respect to the steering axis as soon as the said aeroplane comes out of equilibrium.

Although as illustrated the present invention has been based on what has been described and illustrated in the aforesaid application many modifications may in practice be made without coming out of the scope of the invention.

What I claim as my invention is:

1. In an aeroplane, the combination with the main supporting wings of automatic means for providing longitudinal stability and of automatic means for providing steering stability which comprise a pair of symmetrical vertical surfaces extending in rear of the main wings and arranged substantially parallel to the plane of symmetry of the aeroplane and so that their centres of pressure are in rear of the steering axis.

2. In an aeroplane, the combination with the main supporting wings of automatic means for providing longitudinal stability which comprise a pair of symmetrical rear-

wardly extending horizontal planes so arranged that their centres of pressure are in rear of the pitching axis, of automatic means for providing steering stability which 5 comprise a pair of symmetrical vertical surfaces extending in rear of the main wings and arranged substantially parallel to the plane of symmetry of the aeroplane and so that their centres of pressure are in rear of the steering axis. In witness whereof, I have hereunto signed my name.

ALDO TAMMÉO.
